United States Patent

Des. 242,356
Patented Nov. 16, 1976

242,356

DATA PROCESSOR

Wayne L. Aderman, Zumbro Falls, and Frank Wilkey,
Jr., Rochester, Minn., assignors to International Business
Machines Corp., Armonk, N.Y.

Filed Dec. 24, 1974, Ser. No. 536,078

Term of patent 14 years

Int. Cl. D14—02
U.S. Cl. D26—5 C

FIG. 1

FIG. 2

FIG. 3

FIG. 4

FIG. 5

FIG. 6

FIG. 7

FIG. 8

FIG. 1 is a perspective view of a data processor showing our new design;

FIG. 2 is a left side elevation of the data processor shown in FIG. 1;

FIG. 3 is a rear elevation of the data processor shown in FIG. 1;

FIG. 4 is a bottom view of the data processor shown in FIG. 1;

FIG. 5 is a perspective view of a modified form of the data processor shown in FIG. 1;

FIG. 6 is a left side elevation of the data processor shown in FIG. 5;

FIG. 7 is a rear elevation of the data processor shown in FIG. 5; and

FIG. 8 is a bottom view of the data processor shown in FIG. 5.

The broken line disclosure in FIGS. 1 and 5 is for illustrative purposes only.

We claim:

The ornamental design for a data processor, as shown and described.
